UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

KEYBOARD MECHANISM.

Application filed August 15, 1923, Serial No. 657,473.

To all whom it may concern:

Be it known that I, JOHN R. ROGERS, a citizen of the United States, residing at Brooklyn, in the county of Kings and State 5 of New York, have invented certain new and useful Improvements in Keyboard Mechanisms, of which the following is a specification, reference being had therein to the accompanying drawing.

10 This invention has reference to keyboard mechanisms, such as are employed in commercial linotype machines. In these machines, the escapements controlling the discharge of the matrices from the magazine 15 are actuated by vertical reeds operated by pivoted yokes or levers, each containing a rotary cam or eccentric which is adapted to make peripheral contact with an underlying constantly rotating rubber-covered 20 roll. The pivoted yokes are held normally with their cams at rest and out of contact with the rubber-covered roll and are released by the manipulation of finger keys, which permit the cams to fall into engagement 25 with the driving roll and be rotated thereby to raise the yokes and operate the escapements. In practice, the life of the rubber-covered rolls is comparatively short by reason of wear and other deteriorating 30 influences, and hence it is necessary at times to remove the worn rolls and substitute new ones, involving considerable expense and occasioning much inconvenience and loss of time. In addition, the wear of the rolls 35 oftentimes results in the failure of the escapements to respond to the actuation of the finger keys, due to the insufficient raising of the cam yokes. Furthermore, and without regard to the question of wear, considerable 40 slippage takes place between the cams and the rubber-covered rolls during their driving engagement, and especially when oil finds its way onto the rolls, resulting in a delayed actuation of the matrix-releasing escapements and thus giving rise to trans- 45 positions of matrices in the composed line.

The present invention is intended to do away with the above mentioned rubber-covered rolls and the attendant objections, and 50 contemplates the use of metal rolls for driving the rotary cams or eccentrics. In providing for a driving engagement between these parts, the rolls are formed in their

outer surface with a series of annular V-shaped grooves, and the rotary cams or eccentrics are formed with correspondingly shaped peripheral ribs to engage in said grooves. As the parts are thus formed, when the eccentrics are dropped into engagement with the rolls, the rotary motion 60 of the latter will be imparted immediately to the former and the two caused to rotate in unison, the frictional engagement of their V-surfaces being great enough to ensure this result. In practice, the amount of wear is 65 quite negligible, although such as takes place is fully compensated for by the nature of the driving engagement. These and other improvements will be fully set forth in the detailed description to follow.

70 Referring to the drawings:

Fig. 1 is a vertical section taken through the keyboard mechanism of a linotype machine equipped with the present improvements;

Fig. 2 is a similar view showing one of the cams or eccentrics in operation and with the corresponding yoke in its raised position;

Fig. 3 is an elevation of one of the power 80 driven rolls detached;

Fig. 4 is a section taken on the line 4—4 of Fig. 3;

Fig. 5 is a side view of one of the improved cams or eccentrics detached;

Fig. 6 is a transverse section taken on the line 6—6 of Fig. 5;

Fig. 7 is an enlarged detail view, showing one of the cams or eccentrics out of engagement with the power driven roll;

Fig. 8 is a similar view, showing said cam or eccentric in engagement with the roll;

Fig. 9 is a section taken on the line 9—9 of Fig. 1; and

Figs. 10 and 11 illustrate a modification, Fig. 11 being a section taken on the line 11—11 of Fig. 10.

The matrix-releasing escapements (not shown) are actuated by a series of vertical 100 reeds A, which in turn are operated by horizontally disposed yokes or levers B, arranged as customary in two banks or series and with the inner ends in position to engage the reeds. At their opposite ends, the 105 yokes are supported upon transverse pivot

wires or rods B^2 of the framework; and between their ends, the yokes are provided with rotary cams or eccentrics C journaled thereon as at C^2 , and adapted to be rotated by underlying power driven rolls D , one for each series of yokes. At their inner ends, the yokes B are supported upon angular trip dogs E , which normally hold the yokes at such height as to maintain the cams C out of engagement with the rolls D , the cams in this position of the parts being held against rotation by the engagement of arresting pins C^1 thereon with a transverse stop bar G on the framework. When the trip dogs E are moved, the yokes are tripped and allowed to drop, with the result that the pins C^1 are disengaged from the stop bar G and the cams C (which are weighted at one side, as usual) fall into contact with one or the other of the rolls D , causing the yokes to be rocked upwardly to operate the escapement actuating reeds A (see the dotted-line showing at the left in Fig. 1). The dogs E are controlled by vertical bars F slidably arranged in the framework and operated by key levers H . The foregoing parts and their mode of operation, except as herein-after pointed out, are or may be the same as embodied in the commercial linotype machine, or as illustrated in the Dodge Patent No. 520,931.

According to the present invention, each of the power driven rolls D (which are preferably made of metal) is formed in its outer surface with a series of annular V-shaped grooves D^1 , and each of the rotary cams or eccentrics C is formed with an annular V-shaped peripheral rib C^3 to correspond. Consequently, when any selected one of the cam yokes is tripped by the actuation of its finger key, the rotary cam mounted on such yoke will drop and bring its V-shaped peripheral rib into engagement with the V-shaped groove of the underlying power driven roll, which will thereupon rotate the cam to carry out the escapement releasing operation above described, see particularly Fig. 8. When these parts are in engagement, the friction between their V-surfaces will be quite sufficient to cause them to rotate in unison and without slippage. In the drawings, the angularity of the V-surfaces and the depth of the grooves have been slightly exaggerated for the sake of clearness, but in practice they may be modified to meet the requirements. If desired, the cams may be formed with the V-shaped grooves and the rolls with the V-shaped ribs, although such a formation of the parts (a mere reversal of that described) would be more expensive and less advantageous in other respects. It may also be noted that it is not absolutely essential that both the power driven rolls and the cams be formed with the V-surfaces, as the same effect would be produced

if the rolls alone were formed with the V-shaped grooves, and the cams made of any desired shape to engage the sides of said grooves. As a matter of fact, the invention contemplates any mutual formation of the parts designed to provide for a lateral driving engagement between them. 70

In the present instance, and as preferred, the rotary cams or eccentrics C are of true circular form, and hence, unless provision were otherwise made, there would be no dwell of the yokes B in their raised position such as is desired to allow the matrices to escape from the magazine when released by the operation of their escapements. For 75 this reason, the cams or eccentrics are given a degree of eccentricity more than sufficient merely to actuate the matrix releasing escapements, but great enough to provide for considerable overthrow. To allow for such 80 overthrow, the cam yokes B are formed with vertical open slots B^1 which fit over the pivot rods B^2 , and springs B^3 are attached to the yokes to hold them yieldingly in place upon said pivot rods. As a result, when the cam yokes have been rocked upwardly about the pivot rods, as far as the escapement-actuating reeds will permit, they will then yield upwardly at their pivoted ends to allow the rotary cams or 85 eccentrics to pass dead center (see Fig. 2), after which they will be drawn back upon the pivot rods by the connected springs. During such yielding period, however, the free ends of the cam yokes become fulcruming points and hold the escapement-actuating reeds at rest long enough to allow 90 the released matrices to escape. 95

In the present embodiment, as will be observed, the arresting pins C^1 extend outwardly from the peripheries of the rotary cams or eccentrics C , and the stop bars G , which cooperate with said pins, are plain and solid throughout, this arrangement possessing many advantages over prior constructions. In order to permit such location of the arresting pins, the power driven rolls D are formed with annular channels D^2 , located inward of the V-shaped grooves D^1 and opening thereinto at their apices, thus affording ample clearance for the arresting pins during the rotation of the cams by the driving rolls (Figs. 2 and 8). 100

In Figs. 10 and 11, which show an alternative arrangement, the V-shaped ribs C^3 of the cams or eccentrics C are slightly cut away or recessed, as at C^4 , to provide arresting shoulders C^5 for engagement with the solid transverse bar G , these shoulders C^5 functioning in the same manner as the arresting pins C^1 before described. Inasmuch as the shoulders C^5 are located within the peripheral edges of the cams C , the clearance channels D^2 are not needed, and hence the power driven rolls D may be 110 115 120 125 130

formed only with the V-shaped grooves D¹, which of course engage only the inclined or beveled surfaces of the ribs C³.

When the cam yokes are tripped and the parts set in motion, it is desirable that the trip dogs E be restored promptly to their original position in order to arrest the descending yokes after they have operated the matrix releasing escapements. To attain this result, each cam yoke is provided at its free end with a bent U-shaped piece J (Figs. 1 and 9) arranged in position to engage the upper end of the trip dog as the yoke is rocked upwardly, and thereby throw the dog back to its original position. By reason of its U-shaped form, the piece J will allow the arresting pin C¹ on the associated cam to pass through it without interference.

The foregoing improvements have been shown merely in preferred form and by way of example, and as applied to a mechanism of the class stated, but obviously many modifications and alterations therein and in their mode of application may be made without departing from the spirit of the invention. For instance, the improvements might be applied to a keyboard mechanism of a machine other than the linotype and still function substantially in the manner indicated. It should be understood, therefore, that the invention is not limited to any specific form or embodiment, except in so far as such limitations are set forth in the claims.

Having thus described my invention, its construction and mode of operation, what I claim and desire to secure by Letters Patent of the United States, is as follows:

1. In a mechanism of the class described, the combination with a rotary driving element and a rotary driven element, the two being mutually formed for lateral driving engagement, of an actuating member on which the driven element is journaled and which is operated thereby, and means controlling the engagement and disengagement of said driven element with and from the driving element.

2. In a mechanism of the class described, the combination with a rotary driving element and a rotary driven element, one formed with an annular groove and the other formed to engage the sides of said groove, of an actuating member on which the driven element is journaled and which is operated thereby, and means controlling the engagement and disengagement of said driven element with and from the driving element.

3. In a mechanism of the class described, the combination with a rotary driving element and a rotary driven element, one formed with an annular V-shaped groove and the other with a V-shaped rib to en-

gage in said groove, of an actuating member on which the driven element is journaled and which is operated thereby, and means controlling the engagement and disengagement of the driven element with and from the driving element.

4. In a mechanism of the class described, the combination of a rotary driving element formed with an annular V-shaped groove and with an annular clearance channel opening into said groove at the apex thereof, a rotary driven element formed to engage the sides of said groove, an actuating member on which the driven element is journaled, and means controlling the engagement and disengagement of the driven element with and from the driving element, the said means including an arresting pin extending outwardly from the periphery of the driven element and adapted to travel in the clearance channel of the driving element when said parts are in driving engagement with each other.

5. In a mechanism of the class described, the combination of a rotary driving element formed with an annular V-shaped groove, a rotary circular driven element formed to engage the sides of said groove, a pivoted actuating member on which the driven element is journaled and mounted to yield at its pivoted end, and means controlling the engagement and disengagement of the driven element with and from the driving element.

6. In a mechanism of the class described, the combination of a rotary driving element formed with an annular clearance channel, a rotary driven element, and means controlling the engagement and disengagement of said elements with and from each other, the said means including an arresting pin extending outwardly from the peripheral edge of the driven element and adapted to travel in the clearance channel of the driving element when these parts are in driving engagement.

7. In a keyboard mechanism of the linotype class, the combination of a power driven roll formed in its outer surface with a series of annular V-shaped grooves, a corresponding series of rotary cams formed with V-shaped peripheral ribs to engage in said grooves, pivoted yokes or levers on which the rotary cams are journaled, and means controlling the engagement and disengagement of the cams with and from the power driven roll.

8. In a keyboard mechanism of the linotype class, the combination of a series of pivoted yokes or levers, rotary cams journaled thereon and formed with V-shaped peripheral ribs, a power driven roll formed in its outer surface with a corresponding series of annular V-shaped grooves wherein the cam ribs engage, and also formed with

- clearance channels opening into said grooves at their apices, arresting pins extending outwardly from the peripheral edges of the cams and adapted to travel in said clearance channels, a stop bar arranged to cooperate with said arresting pins, trip dogs associated with the cam yokes or levers, and key controlled actuating slides connected to the trip dogs.
10. 9. Keyboard mechanism as specified in claim 7, characterized by the fact that the rotary cams therein recited are of circular form and that the pivoted yokes or levers on which they are mounted are arranged to yield at their pivoted ends, for the purpose described.
10. 10. In a keyboard mechanism of the line-type class, the combination of a power driven roll formed in its outer surface with a series of annular grooves, a corresponding series of rotary cams formed to engage the sides of said grooves, pivoted yokes or levers on which the rotary cams are journalled, and means controlling the engagement and disengagement of the cams with and from the power driven roll.
10. 11. In a keyboard mechanism of the line-type class, the combination of a power driven roll, a rotary cam adapted to engage therewith, a pivoted yoke or lever on which the cam is journalled, a key controlled trip dog associated with the cam yoke, and a U-shaped piece attached to the cam yoke at its free end and adapted during the operation thereof to engage the trip dog and restore it to its normal position.
10. 12. A keyboard mechanism as specified in claim 8, characterized by the fact that the pivoted cam yokes are provided at their free ends with substantially U-shaped pieces adapted, during the operation of the yokes, to engage the trip dogs and restore them to their normal position, the said U-shaped
- pieces permitting the free rotation of the cams without interference with their arresting pins.
13. In a mechanism of the class described, the combination with a rotary driving element and a rotary driven element, the two being mutually formed for lateral driving engagement, and the driven element having an arresting shoulder located at its outer peripheral edge, of an actuating member on which the driven element is journalled, trip means cooperating with the actuating member to hold the driven element normally out of engagement with the driving element, and a stop device adapted to engage the arresting shoulder of the driven element and hold the latter against rotation.
13. 14. In a keyboard mechanism of the line-type class, the combination of a series of pivoted yokes or levers, rotary cams journalled thereon and formed with V-shaped peripheral ribs, said ribs being formed in their outer edges with notches or recesses to provide arresting shoulders for said cams, a power driven roll formed in its outer surface with a corresponding series of annular V-shaped grooves wherein the cam ribs engage, a stop bar arranged to engage the arresting shoulders of the cams, trip dogs associated with the cam yokes or levers, and key-controlled actuating slides connected to the trip dogs.
13. 15. A mechanism as specified in claim 1, characterized by the fact that the rotary driven elements or cams therein recited are formed in their outer peripheral edges with notches or recesses to provide arresting shoulders for engagement with a stop bar, as and for the purpose described.
- In testimony whereof, I have affixed my signature hereto.

JOHN R. ROGERS.
